UNITED STATES PATENT OFFICE.

ERIK GADDA, OF SILVERTON, OREGON.

CLOTHES HANGER.

Application filed April 13, 1922. Serial No. 552,129.

To all whom it may concern:

Be it known that I, ERIK GADDA, a citizen of Finland, residing at Silverton, in the county of Marion and State of Oregon, have invented certain new and useful Improvements in Clothes Hangers; and I do hereby declare the following to be a full, clear, and exact description of the invention, such as will enable others skilled in the art to which it appertains to make and use the same.

This invention relates to new and useful improvements in clothes hangers especially adapted for supporting coats and trousers and has for its primary object the provision of a device of the above stated character which may be easily and quickly collapsed to permit of the device being conveniently carried or stored in a small space.

Another object of this invention is the provision of a clothes hanger of the above stated character which will be simple, durable, and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which:—

Figure 1 is a front elevation, illustrating a clothes hanger constructed in accordance with my invention,

Figure 2 is a sectional view taken on the line 2—2 of Figure 1,

Figure 3 is a plan view illustrating the device collapsed,

Figure 4 is a detail view illustrating the trouser attaching member and its detachable connection with the brace.

Referring in detail to the drawings, the numerals 1 and 2 indicate the inclined members which have their adjacent ends overlapped and pivotally connected as shown at 3, and the pivotal connection carries a hook 4 whereby the device may be readily sus-

pended from a suitable support. A brace 5 has one end pivoted to the member 2 as shown at 6 while its other end is beveled and has formed thereon an extension 7 adapted to fit within a socket 8 formed in the member 1 for the purpose of establishing a detachable connection between said member and the brace which permits of the brace and members 1 and 2 to be folded 60 one upon the other as clearly shown in the drawings. The parts heretofore described when assembled, as shown in Figure 1, form an efficient coat hanger, and the brace 5 adjacent to its beveled end is provided with a recess 9 in which is located a pivot 10 that extends through an eye formed in the enlarged end 11 of a trousers securing strap or member 12. The member 12 is preferably constructed from flexible material and is 70 provided with compound curves to facilitate its clamping action on the leg portions of trousers when said trousers are positioned between the member 12 and the brace 5. The brace adjacent to its other end is provided with a recess 13 in which is located a pivot pin 14 carrying a U-shaped clamp 15 adapted to be placed over the free end of the member 12 for the purpose of securing said member in parallelism with the brace for the 80 purpose of firmly securing the leg portions of trousers to the brace and when it is desired to remove the trousers, the clamp 15 is swung into the recess 13 freeing the member 12 so that it may be swung upon its hinge 85 or pivot and permit the easy removal of the trousers.

While I have shown and described the preferred embodiment of my invention, it will be understood that minor changes in 90 construction, combination, and arrangement of parts may be made without departing from the spirit and scope of the invention as claimed.

Having thus described my invention what 95 I claim is:—

A clothes hanger comprising a pair of arms arranged in spaced parallel relation, an arm having one of its ends received between said pair of arms, a pivot passing 100 through all of said arms, a brace member having one of its ends received between said

pair of arms, a pivot passing through said arms and said end of the brace member, said brace member having its other end reduced to form a projection and a shoulder, and 5 said second named arm having a socket to receive said projection when the hanger is in set-up condition, the inner edge of the arm having the socket adapted to rest

against the shoulder of the brace when the projection is within the socket.

In testimony whereof I affix my signature in presence of two witnesses.

ERIK GADDA.

Witnesses:

Mrs. C. H. GORSHIR,
C. H. LOSCHIE.
